UNITED STATES PATENT OFFICE.

ABBOTT Q. ROSS, OF CINCINNATI, OHIO.

ROLL-PAPER HOLDER AND CUTTER.

SPECIFICATION forming part of Letters Patent No. 398,750, dated February 26, 1889.

Application filed July 23, 1888. Serial No. 280,758. (No model.)

To all whom it may concern:

Be it known that I, ABBOTT Q. ROSS, a citizen of the United States, residing at Cincinnati, Hamilton county, Ohio, have invented 5 new and useful Improvements in Roll-Paper Holders and Cutters, of which the following is a specification.

My invention relates to that class of roll-paper holders embodying, in combination with the paper roll, a "floating" or gravity friction-bar whose function is to retard the rotative momentum of the roll in withdrawing the paper web preparatory to tearing off a desired portion.

15 An example of the type or class of holders to which my invention is applied is shown in a former application pending herewith, upon which my present invention is in the nature of an improvement. In said other application 20 is shown a floating bar resting by gravity upon the periphery of the roll and upon the free end of the web without adjuncts, and having its front beveled to constitute a "tearing-knife."

25 In my present invention I employ a floating bar guided as in said former application, but provided with a projecting strip of metal constituting a tearing-knife, and with a pivoted drag-bar. The floating bar in this case rests 30 upon the roll beneath the paper strip, the latter passing out over the friction-bar and under the tearing-knife, one of the principal objects of the construction being to cause the free end of the web, after severance of a portion 35 of the same, to remain in such convenient relation to the knife and the paper roll as to facilitate a renewed grasp and avoid the necessity of turning the roll independently to project a new margin for such new grasp.

40 Mechanism embodying my invention is exhibited in the accompanying drawings, in which—

Figure 1 is a general perspective view of the device completed; Fig. 2, a vertical cross-section of the same, and Fig. 3 a detail showing the connection of the floating bar and the tearing-knife.

Referring now to the drawings, A designates the paper roll; B B, the side standards 45 in which the same is journaled, and C a float-

ing bar guided by its end projections, c c, in the vertical slots of the standards. The bar C is flat, and rests one of its flat sides upon the periphery of the roll and follows the same downward by gravity as the roll diminishes in size. Secured across the top of the bar C upon elevated projections a, near each end, is the tearing-knife or straight-edge D, space enough being left between itself and the knife and horizontally between the projections a to allow the passage of the free end of the paper strip outward from the roll beneath the projecting straight-edge. I also arrange a bail-like drag-bar, E, which may be formed of wire pivotally bent, engaging by its end in 65 the guide projections c at each side and passing either outside or inside of the standards.

The function of the drag-bar is to rest upon the roll behind the floating bar C to prevent the free end of the web or strip from being 70 displaced by any accident.

The operation is as follows: The free end of the paper strip or web w is passed out under the drag-bar E, over the floating-bar C, and under the knife D, as shown. The paper is 75 thus perfectly guided between the projections a, and is torn by an upward pull against the knife. The projection of the knife above and in tangential relations to the roll A leaves a considerable vertical interval between the 80 surface of the roll and the outer edge of the knife, and in this space the free end of the unsevered portion partly falls by gravity, as indicated, and remains in convenient position to be regrasped. The drag-bar behind prevents this free end from receding, and the parts thus remain in position for convenient use, and the rotation of the paper roll to project anew a grasping-margin of the strip or web is thus rendered unnecessary. 85

The ordinary action and function of the friction-bar in retarding the revolution of the roll and preventing the overrunning of the web are similar to that of any similarly-mounted friction-bar, and need not be here described. 95

I do not claim herein, broadly, a floating weighted bar adapted to be held by gravity alone against the periphery of a roll of paper and having a cutting edge or knife removed from the point of contact between said bar 100

and roll, as such matter is made the subject of claim in another case filed by me July 31, 1888, Serial No. 281,580.

I claim as my invention and desire to secure by Letters Patent of the United States—

In a paper-roll holder of the character described, the combination, with the standards and their guides, of the friction-bar bearing directly on the roll of paper, and the tearing-knife supported on said friction-bar, but projecting in a plane above the same, so as to leave a clear space between the two and permit the web of paper to pass over the friction-bar and under the tearing-knife, whereby

when the paper is drawn upward against the edge of the knife to sever it the remaining end will drop down by gravity away from the knife, in position to be grasped when the next sheet is desired to be removed; substantially as described.

In testimony whereof I have hereunto set my hand in the presence of two subscribing witnesses.

ABBOTT Q. ROSS.
